UNITED STATES PATENT OFFICE.

HOWARD A. PEDRICK, OF BALA, PENNSYLVANIA.

CALKING MACHINE.

Application filed December 7, 1920. Serial No. 429,032.

To all whom it may concern:

Be it known that I, HOWARD A. PEDRICK, a citizen of the United States, residing in Bala, Montgomery County, Pennsylvania, 5 have invented Calking Machines, of which the following is a specification.

One object of this invention is to provide a relatively simple, substantial and easily operated device for containing and 10 forcibly discharging plastic or semi-solid fluid material, as well as liquids, especially of a viscous nature; and the invention more especially contemplates a novel form of holder having associated with it novel means 15 for causing delivery from it of the contained material.

A further object of the invention is to provide a novel form of "gun" especially adapted to utilize compressed air for the 20 expulsion of the plastic or other material which it contains and which shall be of such construction as to insure the complete delivery of each charge as well as to facilitate its recharging; the arrangement of parts being 25 such as to permit of its rapid, convenient and efficient use.

These objects and other advantageous ends I attain as hereinafter set forth, reference being had to the accompanying drawings, in 30 which,—

Figure 1 is a longitudinal vertical section of a calking machine constructed in accordance with my invention;

Fig. 2 is a front elevation of the structure 35 shown in Fig. 1; and

Figs. 3 to 5 are vertical longitudinal sections of modified forms of the invention.

In Figs. 1 and 2 of the above drawings, 1 represents the body of the gun which is 40 preferably of the frusto-conical form and has at its small or apex end a conveniently removable closure 12 which in the present instance is screwed into it. This closure member has in its inner face a conical recess 13 terminating in a central passage 14 of reduced cross section which is internally threaded or otherwise constructed for the reception of a delivery nozzle 15. Obviously this latter with the closure member may together constitute a delivery nozzle.

The opposite or basal end of the body 1 is outwardly flanged in the present instance and has screwed or bolted to it a plate constituting a head 4, between which and the 45 flange of said body is clamped or confined a flexible diaphragm 2, which in the preferred

embodiment of the invention, is made of resilient material such as sheet rubber. The head 4 is so formed as to provide a chamber 3 between itself and the diaphragm 2 and 60 has connected to it a suitable handle, in the present instance consisting of a pair of posts or studs 6 and 7 projecting outwardly from it and rigidly connected by a hand-hold or equivalent member 5 constituting the body 65 of the handle.

In this form of the invention, the stud 6 is made tubular and has secured on its outer end a three-way cock or valve 9 connected through a conduit 11 to a source of air under pressure. The movable member 16 of 70 this valve is so constructed that the passage 8 through the stud 6 may be placed at will in communication with the air supply conduit 11 or with an exhaust port 10. As a 75 consequence air under pressure may be delivered to the chamber 3 from the conduit 11 or exhausted from said chamber as desired.

Under conditions of use the nozzle member or closure 12 is removed from the body 80 by means of a wrench applied to its hexagonal extremity and any desired plastic material such as putty, calking compounds, grease, etc. may be placed in its main cavity 20. The member 12, with or without the 85 delivery pipe 15, is then screwed into position in the end of the body and by proper manipulation of the valve member 16, air under pressure is delivered to the chamber 3.

The diaphragm 2 is thereupon forced 90 against the mass of plastic material in the chamber 20 causing this to be discharged through the nozzle, being also pressed by the air against the inclined sides of the body so that all of the material adhering thereto 95 is forced out. The rate of delivery of the material may be regulated by the valve member 16 and when the body has been emptied, said member of the valve is turned to permit the air confined between the diaphragm 2 100 and the head 4 to be exhausted, whereupon said diaphragm returns to its original position by virtue of its resiliency. The member 12 may thereupon be removed and another charge of material placed in the body. 105

If desired I may also construct my device as shown in Fig. 3 in which case the body or plastic-containing structure consists of two substantially similar cup-shaped structures 21 and 22, preferably having their 110 edges flanged and having confined between them a diaphragm 2^a of a flexible material.

- such as leather or the like, of such shape that it will completely or approximately conform to or lie against the inner surface of either of the body members 21 and 22.
- 5 Of these, the former is provided with a delivery nozzle member 12^a and the latter structure has connected to or formed integral with it a handle structure 23 formed with a passage 24 which at its outer end is connected through a valve 9 with a suitable air source. As before, the inner end of the passage terminates at the center of the inner face of the body member 22, although it is obviously immaterial as to just where this 10 passage enters or where the air controlling valve is placed so that it is possible to deliver the air to and exhaust it from the space between the diaphragm 2^a and the inner face of the cup-shaped member 22.
- 15 20 The plastic or other material to be delivered by the device is introduced into the chamber 20^a between the diaphragm 2^a and the body member 21 either through the opening provided by removing the nozzle member 12^a or in any other manner. Thereafter air under pressure is admitted through the valve 9 and the passage 24, and the flexible diaphragm 2^a acts on the material in the body to force it out through the passage 25 30 in said nozzle member. Instead of removing the nozzle member when it is desired to fill the device I may provide the body with a side opening normally closed by a conveniently removable plug or cap 25 as shown in Fig. 4 or the body may be screwed to or otherwise made to be easily detachable from the head as shown in Fig. 5. In the latter case the diaphragm is preferably clamped to the head by means of a ring 26 held in 35 40 place by screws 27 so that said head and body may be separated to permit of the lat-

ter being filled, and thereafter reconnected prior to the introduction of air to the chamber 3 when the plastic material in the body is to be expelled.

45 In any case the material in the body of the device is forcibly and completely delivered therefrom and such delivery may be conveniently controlled by the valve 9. Moreover the device may be quickly refilled, 50 and since the air under pressure acts on the material through the medium of the diaphragm, it does not tend to blow through said material without ejecting it, as is the case when the latter is semi-solid or exceptionally viscous, but on the contrary causes it to be completely delivered at any desired rate.

55 I claim:

1. The combination of a casing of substantially conical form having a normally closed filling opening in its side; a removable outlet nozzle at the smaller end of said casing; a flexible diaphragm mounted at the basal end of the casing; a head for the casing mounted to cooperate with the diaphragm to form an air chamber; and means for delivering air under pressure to said air chamber to force the diaphragm into the conical portion of the casing. 60

70 2. The combination of a casing having an outlet; a head for said casing; a flexible diaphragm confined between the casing and the head; a handle mounted on the head and having a tubular portion; and means for controlling the flow of air under pressure through said tubular portion to the chamber defined by the head and the diaphragm for causing said diaphragm to expel material in the casing through the outlet. 75

HOWARD A. PEDRICK.
